UNITED STATES PATENT OFFICE

CLYDE B. HICKS, OF ABILENE, TEXAS

DIPPER DEVICE

Application filed August 9, 1929. Serial No. 384,750.

This invention relates to a dipper device designed primarily for use in connection with thermos jugs, but it is to be understood that a dipper device, in accordance with this invention may be employed in any connection for which it is found applicable, and the invention has for its object to provide, in a manner as hereinafter set forth, means to enable one to conveniently remove the fluid contents of a thermos jug when desired.

As is well known, generally, when pouring water from a thermos jug, especially of a gallon size into an ordinary size drinking cup, there is spilt about as much water as is 15 poured into the cup, and further if water is desired to be poured from the jug, when the latter is carried by a motor vehicle, it necessitates the vehicle to be brought to almost a full stop before the pouring action is attempted and when attempted, that is pouring from the jug into the cup, it generally results in the spilling of the water within the vehicle. To overcome this objectionable spilling, as well as the slowing of the vehicle 25 when it is desired to pour water from a thermos jug is the primary object of this invention, and which is attained by a dipper device constructed in a manner as hereinafter set forth and which includes a handle element 30 formed of a pair of detachable sections, one pivotally connected to the dipper body and of a length to be housed within the dipper body within the jug, and further of a length to extend into the neck of the jug whereby such 35 section is maintained in an upright position to be readily grasped by the user from within the neck of the jug. The other of the sections is to be carried exteriorly of the jug and is capable of being coupled, in the jug neck with 40 the section which is housed within the jug and when that section is employed, such section being the section for extension into the jug neck, it overcomes the necessity of the user positioning his hand within the neck of 45 the jug to remove the dipper body.

Further objects of the invention are to provide, in a manner as hereinafter set forth, a dipper device which is simple in its construction and arrangement, strong, durable, thoroughly efficient in its use, conveniently re-

moved from the jug and inexpensive to manufacture.

With the foregoing and other objects in view the invention consists of the novel construction, combination and arrangement of parts as hereinafter more specifically described, and illustrated in the accompanying drawings, wherein is shown an embodiment of the invention, but it is to be understood that changes, variations and modifications 55 can be resorted to which fall within the scope of the claims hereunto appended.

In the drawings wherein like reference characters denote corresponding parts throughout the several views:

Figure 1 illustrates in dotted lines a thermos jug showing the adaptation therewith of a dipper device in accordance with this invention and with the outer section of the handle member not shown and with the inner section of the handle member and dipper body 60 illustrated in side elevation.

Figure 2 is a view similar to Figure 1 illustrating in side elevation a dipper device in accordance with this invention in position 65 with respect to a jug and further showing the sections of the handle member detachably connected together with the outer section extended from the neck of the jug.

Figure 3 is a perspective view of a dipper device in accordance with this invention with the outer section of the handle member removed.

Figure 4 is a perspective view of the outer section of the handle member.

Referring to the drawings in detail 1' denotes the body portion of a thermos or other jug and 2' the neck thereof.

The dipper device, in accordance with this invention includes a dipper body 1 and a handle member formed of an inner and an outer section referred to generally at 2, 3. The sections of the handle member are detachably connected together.

The dipper body is of any desired capacity, 95 of bucket-like form and gradually decreases in diameter from its bottom to its open top. It is to be understood however that the dipper body 1 can be of any suitable contour. The dipper body 1 in proximity to its top edge 4 100

is provided with a pair of diametrically opposed openings 5, 6.

Each section of the handle member is formed from a single length of wire of the desired gauge. The section 2 includes an intermediate portion 7, a loop-shaped outer portion 8 of substantially rectangular contour and a bail-shaped inner portion 9 of greater length than the outer portion 8 and having the arms 10 thereof formed at their free ends with inwardly extending portions 11 which project through the openings 5, 6 and provide pivots for the dipper body 1. The inwardly extending portions 11 are oppositely disposed and arranged at right angles with respect to the arms 10 of the bail-shaped portion 9. The arms 10 are disposed at opposite inclinations and are coupled with the dipper body 1 and such arms are resilient so that they will tend to maintain the inwardly extending portions 11 in coupled engagement with respect to the dipper body 1. The section 2 is of a length, that when the dipper body 1 is supported upon the bottom of the body portion 1 of the jug, said section 2 will extend into the neck 2' of the jug whereby the section 2 will be maintained in an upright position and can be readily reached by the user when desired.

The sections 3 include an outer end portion in the form of a spring loop 9, a pair of resilient arms 10, 11 and each of the latter terminates in a coupling portion consisting of a pair of parallel, spaced parts 12, 13 and with the outer ends of the parts 12, 13 connected together by an inwardly directed, U-shaped part 14. The inner end of part 13 is formed with a U-shaped extension 15 arranged parallel to the U-shaped part 14 and said part 14 and extension 15 form seats adapted to receive a side portion 16 of the looped outer portion 8 of the section 2. The parts 12, 13 are angularly disposed with respect to the arms 10, 11 and are disposed in planes parallel to the side portions 16 of the looped outer portion of the section 2.

The coupling portions formed on the arms 10, 11 are adapted to be inserted in the looped outer portion 8 of section 2 and to overlap such side portions whereby the section 3 is detachably connected to the section 2. The section 3 can be inserted into the neck 2' of the jug and detachably coupled with the section 2 of the handle and by this arrangement it does not necessitate the hand of the user extending into the neck 2' of the jug.

The dipper device provides a convenient means for removing the fluid content of the jug when occasion requires and overcomes the objections heretofore pointed out when pouring the water or fluid from the jug into a cup. The dipper body 1 and handle section 2 will be permanently arranged within the jug and when the device is desired for use, it does not necessitate the slowing of the mo-

tor vehicle as the contents of the jug can be removed through the medium of the dipper device. When the jug is empty the handle section 3 can be stored therein if desired, preferably by attaching handle section 3 to handle section 2 in a position reverse to that shown in Figure 2.

It is thought the many advantages of a dipper device, in accordance with this invention can be readily understood, and although the preferred embodiment of the invention is as illustrated and described, yet it is to be understood that changes in the details of construction can be had which fall within the scope of the invention as claimed.

What I claim is:

1. A dipper device for removing the contents of a jug including a dipper body of bucket-like form, and a handle section pivotally connected therewith at one end of said body, said dipper body and handle section for storing completely within the jug and said handle section of a length to have its outer end abut the lower part of the inner face of the neck of the jug whereby said section is maintained in an upstanding position to be conveniently grasped for removal from the jug, said outer end in the form of a loop extending in the same plane as the remaining part of said section.

2. A dipper device comprising a dipper body closed at one end and open at its other end, a handle section including a bail portion pivotally connected to said dipper body in proximity to the open end of the latter, said handle section further including a looped outer portion, and an outer handle section having opposed coupling portions at its inner end for extension in the looped portion to overlap the sides of the latter whereby said outer section is detachably connected to said inner section.

3. A dipper device including a dipper body for storing within a jug, and a handle section formed from a single length of material bent to provide an inner portion of bail-like form pivotally connected to said dipper body and an outer portion of loop like form; said handle section for storing within the jug and of a length to be completely positioned within and to have the outer end of its outer portion to abut the inner face of the neck of the jug whereby such outer portion will be in convenient reach of the user within the neck to remove said section and dipper body from the jug.

4. A dipper device including a dipper body for storing within a jug, a handle section having an inner portion of bail-like form pivotally connected to said dipper body, said handle section for storing within the jug and of a length to extend within and to abut the inner face of the neck of the jug whereby said section will be in convenient reach of the user to remove the sections of the

dipper body from the jug, said section having a looped portion at its outer end, and an outer handle section provided with resiliently supported coupling portions for connection to said looped portion to detachably connect said sections together.

5. A dipper device for storage within a jug, including a dipper body and a handle section formed of a single length of material 10 twisted together and bent to provide its inner end in the form of a bail pivotally connected to said dipper body and its outer end in the form of a loop, said section of a length to be completely positioned within and have its 15 looped end abut the lower part of the neck of the jug whereby said section is maintained in an upright position when stored within the jug.

6. A dipper device including a dipper body 20 of bucket like form for storing within a jug, said body having diametrically opposed openings in proximity to its open end, a handle section having its inner part of bail like form provided with opposed, oppositely extending inwardly disposed portions positioned 25 within the openings for pivotally connecting said body to said section, said section further having its outer part of loop like form extending in the same plane as said inner part, 30 and said section for storing within the jug and of a length to have the outer end of said outer part to abut the inner face of the neck of the jug to be conveniently grasped for removal.

35 In testimony whereof, I affix my signature hereto.

CLYDE B. HICKS.
